Primary Examiner — Wan Laymon*Assistant Examiner* — Mark Booker(74) *Attorney, Agent, or Firm* — Hanley, Flight & Zimmerman, LLC(57) **CLAIM**

The ornamental design for an "endoscope system workstation," as shown and described.

DESCRIPTION

FIG. 1 is a front view of an endoscope system workstation. FIG. 2 is a rear view of the endoscope system workstation of FIG. 1.

FIG. 3 is a left side view of the endoscope system workstation of FIG. 1.

FIG. 4 is a right side view of the endoscope system workstation of FIG. 1.

FIG. 5 is a top view of the endoscope system workstation of FIG. 1; and,

FIG. 6 is a bottom view of the endoscope system workstation of FIG. 1.

The broken lines in the figures represent portions of the endoscope system workstation that form no part of the claimed design.

1 Claim, 6 Drawing Sheets(56)
